REFRIGERATING APPARATUS

Lawrence A. Philipp, Detroit, Mich., assignor to
 Kelvinator Corporation, Detroit, Mich., a corporation of Michigan

Application August 14, 1934, Serial No. 739,746

2 Claims.

(Cl. 62—3)

My invention pertains to refrigerating systems and more particularly to cooling means for dissipating heat from refrigerant condensers and compressors.

5 It is an object of my invention to provide an improved cooling system for refrigerating systems to efficiently dissipate the heat from the system with the minimum quantity of cooling means.

10 It is also an object of my invention to provide a refrigerating system with means to automatically regulate the quantity of cooling medium used in accordance with the heat to be dissipated.

15 It is a further object of my invention to provide a refrigerating system with a refrigerant condenser and a refrigerant compressor cooled by the same automatically regulated cooling water.

20 More specifically it is an object of my invention to provide a water cooled refrigerant condenser and a water cooled refrigerant compressor with means for automatically admitting a regulated quantity of water to the condenser and means for conducting a divided portion of the 25 cooling water to the compressor from the condenser.

25 The invention itself, however, both as to its organization and its method of operation, together with additional objects and advantages 30 thereof, will best be understood from the following description of specific embodiments, when read in conjunction with the accompanying drawing, in which the single figure of the drawing is a diagrammatic view representing a refrigerating system provided with a cooling system in accordance with my invention.

35 Referring more particularly to the drawing the apparatus comprises a refrigerant evaporator 1 from which refrigerant vapor is drawn through 40 a suction line 2 by a compressor 3. As the compressor operates it compresses the refrigerant vapor which is conducted through a conduit 5 into a condenser 6 where its latent heat of vaporization is absorbed by a succession of coils 11 through which water or other cooling medium passes. As the temperature of the compressed refrigerant vapor is lowered by contact with the cooling coils it is liquefied. The liquid refrigerant passes through a conduit 13 to the evaporator 1. The admission of liquid refrigerant to the evaporator from the condenser 6 may be controlled through conduit 13 by a valve 16 in the evaporator chamber which is actuated by an associated float 17 and lever mechanism 18 although my invention is not limited to systems of

this type and other known regulating arrangements may be used.

For the purpose of removing the heat generated by the operation of the compressor a water jacket 21 is provided in spaced enclosing relation around the cylinder and cylinder heat of the compressor. The water jacket 21 of the compressor is connected through a conduit 22 to the outlet pipe 23 from the cooling coils 11 in the condenser. A drain pipe 24 extends from a discharge orifice 10 in the water jacket to carry the cooling water to the waste. A branch conduit 28 is connected from an intermediate point on the conduit 22 between the compressor and the condenser and it also discharges water to the waste through a 15 restricted orifice 29. The restricted orifice 29 is selected to have a proper cross sectional discharge area to build up sufficient back pressure to cause a suitable portion of the cooling water from the condenser to circulate around the compressor jacket 21. In actual practise the portion 20 of condenser cooling water to be passed around the compressor may be about ten percent. For example if 10,000 pounds of cooling water per hour must pass through the condenser it 25 would be sufficient to pass about 1,000 pounds of water around the compressor per hour.

It will be apparent that the pipes 23, 28 and 30 which carry cooling water to and from the condenser 6 must be very heavy pipes of large 35 diameter. But the pipe 22 which conducts the water to the compressor may be a light pipe of relatively small diameter which may be readily extended to the compressor even though it be 40 remotely situated. This is a very important advantage of the present installation.

The inlet end of the cooling coil in the condenser 6 is connected to the city water mains through a regulating valve 32 which is automatically adjusted by a thermo responsive device. 40 The temperature responsive device for regulating the flow of water may comprise a bulb 33 which is mounted within the condenser 1 and connected through a small pipe 34 into a flexible metal bellows 35 mounted adjacent the valve. 45 The thermo bulb 33 contains a volatile refrigerant or other liquid which will boil and generate vapor pressure when the temperature in the condenser 6 to which it is exposed rises above a predetermined value. The vapor pressure generated within the thermo bulb 33 is transmitted through the small pipe 34 into the flexible bellows 35 which is thereby distended and actuates the water regulating valve 32 through a connecting rod 36 and crank mechanism 37 to 50 55

accordingly regulate the flow of water into the condenser from the water mains.

During the operation of the compressor the volume of the cooling water admitted is regulated in accordance with the temperature conditions within the condenser. After the water passes from the condenser 6 through conduits 22 and 28 a portion of it is backed up by the pressure set up in the restricted discharge orifice 29 and flows through the compressor cooling jacket 21.

It will be seen that I have provided a refrigerating system with cooling means wherein the quantity of cooling medium used for the condenser and compressor is automatically regulated by a single thermostatic valve in accordance with the temperature conditions of the system and the cooling medium is efficiently utilized and divided between the various elements to be cooled whereby a small flexible conduit may be utilized to carry the cooling water to the compressor.

While it is necessary for the purpose of illustration to describe the disclosed form of my invention in detail, it will be apparent that the invention is not so limited, and that other forms and applications thereof are embraced within the scope of the appended claims.

I claim as my invention:

1. In a refrigerating system the combination of a water cooled refrigerant condenser, a refrigerant compressor having a water cooling jacket, conduit means for passing cooling water to said condenser, a discharge conduit for leading water from said condenser to an adjacent discharge, a restricted orifice interposed in said discharge conduit, and a conduit connected to said discharge conduit at a point between the condenser and in advance of the restricted orifice for conducting a portion of the discharged cooling water to the cooling jacket of the compressor. 5 10

2. A refrigerating system comprising a fluid cooled condenser, a refrigerant compressor, a jacket extending around at least a portion of said compressor, conduit means for conducting cooling fluid to said condenser, pressure reducing means associated with said conduit means, and additional conduit means connected to the first conduit means ahead of said pressure reducing means for conducting a portion of said cooling fluid to said jacket. 15 20 25
